UNITED STATES PATENT OFFICE.

JAMES E. LEADLEY, OF CAMDEN, NEW JERSEY, ASSIGNOR OF ONE-HALF TO
JOHN HANLON, OF NEW YORK, N. Y.

PROCESS OF AND APPARATUS FOR MANUFACTURING GAS.

SPECIFICATION forming part of Letters Patent No. 289,260, dated November 27, 1883.

Application filed June 19, 1883. (No model.)

To all whom it may concern:

Be it known that I, JAMES E. LEADLEY, of Camden, in the county of Camden and State of New Jersey, have invented certain new and useful Improvements in Process of and Apparatus for Manufacturing Gas; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

This invention relates to the manufacture of gas by the decomposition of steam, the distillation of bituminous or soft coal, and by carbureting the gases resulting from such operations with liquid hydrocarbons in a heated vaporizing and mixing chamber, and finally combining and fixing the mixture of gases and vapors in a heated chamber, and thereby forming a homogeneous gas, suitable for heating or illuminating purposes. The object of the invention is to produce a better operating apparatus for distilling the rich illuminating-gases from bituminous coal in a furnace-chamber, without subjecting the coal to an injuriously-high heat.

The invention is embodied, principally, in the improved apparatus, as hereinafter described, and particularly pointed out in the claims.

The invention is illustrated by the accompanying drawings, forming a part of this specification, and in which Figure 1 represents a front elevation of the generating-furnace. Fig. 2 represents a vertical section through the furnace. Fig. 3 represents a vertical longitudinal section at right angles to Fig. 2, through the furnace, the vaporizing and mixing chamber, and the fixing-chamber. Fig. 4 represents a horizontal section on the line $y-y$ of Fig. 3. Fig. 5 represents a horizontal section on the line $x-x$ of Fig. 3. Fig. 6 represents a top or plan view of the apparatus.

The generating-furnace A is set upon a brick-work or stone foundation, x . It is constructed of fire-brick and covered by a jacket of riveted plates of boiler-iron, and is divided into two chambers, one above the other. The lower chamber, B, is the larger in diameter, and is

for decomposing steam. The smaller one, B', is divided from the lower end by a perforated or open-work fire-brick arch, b , placed at the contracted upper portion of chamber B, and is for containing bituminous coal to be distilled for the production of gas. The chamber B has two chutes, $a a$, one on each side at its top, for the admission of coal. The chutes connect with the charging apparatus CC, consisting each of cylinders mounted on a revolving plate, having openings which may be turned to register with the mouth of the chute, and a water-cooled base, upon which the pivoted revolving plate, carrying the cylinders, is supported, all as particularly described in a previous application filed May 4, 1883, and bearing serial number 93,924. The chamber B' is provided with a like charging apparatus, C, mounted upon its top. An air-blast pipe, D, extends vertically up the side of the furnace A, and is provided with a branch, d , having a valve which connects with the ash-pit of the generating and decomposing chamber B, and a branch, d' , having a valve which connects with the top of such chamber, and a branch, d'' , having a valve which connects with the upper part of the coal-distilling chamber B'. Steam-pipes E E, having valves, connect with the base of the decomposing chamber B. The chambers B B' have each, near its base, an opening and tight-fitting door for the removal of ashes and coke.

The mixing and vaporizing chamber F is built of fire-brick, supported on the foundation x , and is covered by riveted plate of boiler-iron. It is provided internally with baffle-plates f , of fire-brick or other suitable material, extending alternately from opposite sides, inclined downward and inward, and overlapping, as shown, to form a zigzag passage for the gases and vapors. This chamber is provided with a smoke-stack, I, having a tight-fitting lid, i , and it is connected to the decomposing-chamber B, near its top by pipe G, having a water-cooled valve, g , which is described and claimed in a separate application. It is also connected to the coal-distilling chamber B', near its top, by pipe H. An oil-supply pipe, h , connects with its upper part for discharging hydrocarbon oil on the baffle-plates for enriching the gas from the generating-chambers. The vaporizing and

mixing chamber F connects with the fixing-chamber L by a pipe, K, at the base. Chamber L is constructed of fire-brick covered by riveted plates of boiler-iron, and is provided with a smoke-stack, l, having a lid or cover, l'. It is also provided with a large central flue, M, open at the top and connecting at the bottom with a pipe, N, leading out of the chamber. The flue M is provided with a wide spiral flange, m, extending from its outer surface to the inner wall of chamber L, and from bottom to top of the tube. This construction of the tube and flange set in the chamber provides a long spiral passage, with a large heating-surface, for the passage of the gases to be combined and fixed. The pipe N leads to a steam-boiler, or directly to a wash and seal box, as preferred. The air-pipe D also connects by branches D' D'' with the chambers F and L, as shown in Figs. 4 and 5, to supply air for supporting combustion in these chambers of gaseous products while heating up the apparatus.

Preparatory to the manufacture of illuminating or heating gas for storage the entire apparatus is heated up by internal combustion. A fire is first kindled in chamber B, and combustion therein is urged by an air-blast till a body of fuel, several feet thick, composed of coke or anthracite coal, which is gradually fed in, is raised to an incandescent state, and the other chambers—the mixing and vaporizing chamber and the fixing-chamber—are raised to the desired temperature by the combustion, within them, of the hot gaseous products, containing a valuable per cent. of carbonic oxide from the fuel in chamber B. The air-blast may be admitted to the upper portion of chamber B for burning the carbonic oxide above the fuel for heating chamber B, and after the chamber is partially heated it may be gradually charged with bituminous coal by the charging apparatus C'. The gases driven off from this coal while the air-blast is on are burned above the fuel and the hot products of combustion conducted into chamber F through pipe H, and then passed into and through chamber L. Should the combustion of the gases be incomplete in the first chamber, the air-blast may be admitted into the succeeding chambers by opening the valves in branch pipes D' D'', and combustion therein completed.

During the operation of heating up the apparatus the products of combustion pass off at pipe N, or through either of the smoke-stacks I or l. All of the chambers being heated to the desired temperature and a bed of incandescent fuel obtained in chamber B, all the air-blast pipes are closed by their valves, the smoke-stacks are closed, and steam is admitted by pipes E into the lower portion of the bed of incandescent fuel in chamber B, where it is decomposed. The resulting hot gases (hydrogen and carbonic oxide) are passed up through the distilling bed of bituminous coal in chamber B', and carry off the rich carbureted hydrogen gas evolved therefrom. The tarry va-

pors are also carried over into chambers F and L and combined with the hydrogen of the decomposed steam, and converted into a fixed gas. Should the gases from the chambers B and B' be deficient in illuminating-power, and in case an illuminating-gas of high candle-power is desired, then hydrocarbon oil is admitted by pipe h upon the baffle-plates f in the top of vaporizing-chamber F, where it is vaporized and mingled with the gases resulting from the decomposed steam and that distilled from the coal, and the entire mixture is combined and fixed in chambers F and L.

The production of gas is continued, as above described, till the bed of fuel in chamber B and the chambers connected therewith are reduced too low in temperature for successful operation. Then the steam and oil are shut off, the lids of the stacks are opened, and the air-blasts are again admitted to the various chambers, as desired, for raising the fuel to incandescence and burning the gaseous products in order to heat the chambers. The gaseous products arising from the combustion of fuel in the decomposing-chamber B may be conducted directly into chamber F through pipe G by opening valve g. This may be desirable, instead of passing such products through chamber B', and thereby carrying off and burning too large a volume of rich gas from the bituminous coal in such chamber. Chamber B may be newly charged with coal or coke just before or just after the air-blast is admitted, and chamber B' may receive a fresh charge of bituminous coal just after the operation of heating up and after the air-blast is shut off, in order to save the rich gases distilled therefrom. In case the coke resulting from the distillation of bituminous coal is not sufficiently decomposed to fall through the openings in the arch b, it is removed through the doorway just above the arch. During the operation of heating up the apparatus the body of fuel in chamber B' may be highly heated by burning the gases at the top of the chamber B, and conducting the resulting hot products of combustion up through the fuel in chamber B', and thence through chambers F and L. In case the fuel in chamber B' is thus heated, it serves to convert any carbonic acid that may pass off from chamber B, while steam is being admitted, into carbonic oxide, or to fully decompose any steam which may escape decomposition in the lower bed of fuel. This would be a desirable method of operating when heating-gas was being manufactured, and in that case no coke need be removed from chamber B'.

Having described my invention, what I claim, and desire to secure by Letters Patent, is—

1. The process of generating gas, which consists in first raising a body of fuel to an incandescent state by a blast of air, heating a separate body of bituminous coal by the resulting hot gaseous products, and burning the gaseous products in the mixing and fixing chambers, then decomposing steam in the first body

of incandescent fuel, passing the resulting hot gases through the body of bituminous coal, and thereby distilling and carrying off the carbureted hydrogen therefrom, carbureting the 5 gases with liquid hydrocarbon, and mixing the gases and vapors in a separate chamber, and finally converting them into a fixed gas in a separate heated fixing-chamber.

2. The generating-furnace, consisting of the 10 upper and lower fuel-chambers, separated by a perforated partition, in combination with the mixing-chamber and the two connecting-pipes H and I, one from each fuel-chamber, as described.

15 3. The generating-furnace, composed of the lower decomposing-chamber, having air and steam supply-pipes, the upper distilling-chamber, and a perforated arch or partition between them, in combination with a fuel-charging apparatus connected with the lower chamber, a 20 fuel-charging apparatus connected with the upper chamber, and a gas-outlet pipe, as and for the purpose described.

4. The generating-furnace, divided into an upper and lower chamber by a perforated partition, in combination with the charging apparatus connected with each, the vaporizing and mixing chamber having an oil-inlet pipe, and a pipe connecting the latter chamber with one of the chambers of the generator, as de- 25 30 scribed.

5. The generating-furnace constructed with two chambers, and provided with air and steam inlet-pipes, in combination with the charging apparatus, the mixing and vaporizing chamber, the fixing-chamber, and the connecting-pipes, as described.

In testimony that I claim the foregoing as my own I affix my signature in presence of two witnesses.

JAS. E. LEADLEY.
